UNITED STATES PATENT OFFICE.

THOMAS A. GAMBINO, OF BOSTON, MASSACHUSETTS, ASSIGNOR TO UNITED LACE & BRAID MANUFACTURING COMPANY, A CORPORATION OF RHODE ISLAND.

RUBBER LIFT FOR BOOTS AND SHOES.

1,266,578.

Specification of Letters Patent. Patented May 21, 1918.

Application filed November 24, 1917. Serial No. 203,653.

To all whom it may concern:

Be it known that I, THOMAS A. GAMBINO, a citizen of the United States, residing at Boston, in the county of Suffolk and State 6 of Massachusetts, have invented certain new and useful Improvements in Rubber Lifts for Boots and Shoes, of which the following is a specification.

My invention relates to rubber lifts for 10 boot and shoe heels and it has for its object to provide an improved article of this kind.

My improved rubber heel lift is molded on a concavo-convex shape, the convex side being the tread or outer surface of the lift, 15 and the concave the inner side which seats against the leather shoe heel when attached. It differs from concavo-convex type of heel lifts as heretofore constructed, however, in that it is made thinner at its middle than at 20 its margin, and is provided upon its concaved side with an elevation or boss, the thickness of the lift from the top of this boss or elevation to the tread side of the lift being preferably less than the thickness at

25 the edge of the lift. The preferred construction of my improved lift also provides a beveled marginal area bordering the inner or top side of the lift which extends inwardly from the edge, or from near the 30 edge. This beveled marginal portion contacts with the edge or corner of the shoe heel when placed in position upon the latter preparatory to nailing, leaving the middle portion of the lift, including the boss or elevation, supported out of contact with the 35 surface of the shoe heel, and when nails are driven through the lift and into the shoe heel to secure the lift in position, the latter is flattened down against the heel but with 40 only the beveled marginal portion and the top of the boss or elevation in contact with the heel. Other features of my invention are hereinafter pointed out.

Referring to the drawings:

45 Fig. 1 is a side elevation of my improved lift for boots and shoes.

Fig. 2 is a plan view of the inner or top side of the lift.

50 Fig. 3 is a plan view of the tread side of the lift.

Fig. 4 is a section on line 4—4 of Fig. 2.

Fig. 5 is a section on line 5—5 of Fig. 2.

Fig. 6 is a sectional view of the lift applied to a shoe heel, showing the same before it is trimmed to fit the heel.

My improved heel lift 1 is made of sufficient thickness to provide a suitably elastic cushion and corresponds in outline to the outline of the usual boot or shoe heel. The tread or outer side 2 of this lift is convex 60 and preferably smooth while the top or inner side 3 is concave, the latter being peculiarly shaped so that the lift is considerably thinner at and near its middle *a* than at its edges *b*. This concaved side is also 65 formed with a boss or elevation 4 molded thereon which may be in the form of a horseshoe shaped ridge, disposed parallel with the outer edge of the lift and extending from a point near one side of the breast 70 5 around the lift to a point near the opposite side of said breast. The thickness of the lift from the top of this boss to the tread side surface 2 is less than the thickness of the lift at its edges *b*, but greater than the 75 thickness at the middle of the lift. To show this difference the line *w—x*, parallel with the tread side surface 2, has been applied to Fig. 5 of the drawings.

The thickness of the marginal portion of 80 the lift throughout the circuit of the latter diminishes toward the middle of the lift, that is, said marginal portion is thickest at the edge of the lift and gradually decreases in thickness toward the middle of the lift 85 owing to the provision of beveled surfaces 6 and 7 upon the top side of the lift, the beveled surface 6 extending from one side of the breast around the rear part of the lift to the opposite side of the breast and the 90 beveled surface 7 extending across the breast of the lift.

When the lift is applied to the heel 9 of a boot or shoe the beveled marginal portions 6 and 7 first contact with the edge of the heel so that it is necessary to bend the lift into flat shape in order to seat the boss or ridge 4 upon the heel. The lift is fastened to the heel 9 by nails 8, as usual, said nails being driven through metallic washers 10 100 incorporated in the lift when it is molded and cured. As will be clear these washers 10 are preferably alined with the boss or ridge 4 so that the nails are driven through the latter. Also it will be clear that when the lift is fastened in place on the heel an air tight suction and cushion chamber 11 is provided between the heel and lift which makes the lift more resilient than those heretofore used. At the same time, since only 110

marginal portions 6 and 7 and the top of ridge 4 are seated against the heel 9, the lift fits itself to the surface of the heel more readily than heretofore and it is unnecessary 5 to smooth off and finish the heel to the degree that has been necessary with heel lifts of this class as heretofore constructed.

The difference between the thickness of the lift at its edge and the thickness through 10 the lift at the boss or ridge, is provided in order that the lift may be adapted for use upon a heel of any one of many different sizes. That is, a relatively large heel engages the beveled surfaces 6 and 7 on a 15 line higher and farther away from boss 4 than does a smaller heel, and although the distance between the top surface of boss 4 and the surface of the heel will vary accordingly, being greater with a large heel 20 than with a smaller one, it will be clear that by making the lift sufficiently thinner through the boss portion than at the edge it is rendered applicable to any one of several different sizes, but in each case the lift 25 is stressed and flattened so as to establish intimate contact between the marginal portions thereof and the edge of the heel, and to bring the boss 4 against the heel, by the fastening nails.

30 After driving the fastening nails 8 the lift may be trimmed at its edge as usual.

Heretofore concavo-convex heel lifts have been molded with their inner concaved surface parallel with their outer convex surface, thus making the lift of uniform thickness throughout and requiring that the inner surface of the lift be fitted to the flat surface of the shoe-heel throughout its area. That is, it was necessary to smooth off or 35 level the entire area of the surface of the shoe heel in order to properly prepare it to receive the rubber lift for the reason that any elevation, particularly an elevation near the margin of the shoe heel would 40 prevent the marginal portion of the rubber lift from properly seating upon the edge of the shoe-heel. The use of my improved heel lift does not require such careful preparation of the shoe heel.

50 While I have shown in the drawings a lift with a boss or elevation 4 extending in a solid line around the concave surface from one side of the breast to the opposite side, I do not mean to confine my invention to that particular construction for it will be apparent that a non-continuous ridge or elevation will effect substantially the same result, such for instance as individual bosses or elevations alined with the washers 55 and nail holes. It will also be obvious that the elevation 4 need not necessarily be a narrow ridge as shown in the drawings, and that such elevation may extend side-

wise toward the center of the lift, but preferably of no greater depth in any part of 65 its surface than it is at the outer edge thereof.

What I claim is:—

1. A rubber lift for boots and shoes made concavo-convex with the middle portion 70 thereof thinner than the marginal portion and having an integral boss upon its top side to seat against the shoe heel when the lift is applied thereto.

2. A rubber lift for boots and shoes made 75 concavo-convex with the middle portion thereof thinner than the marginal portion; an integral boss upon the top side of the lift to seat against the heel when the lift is applied thereto; and a nail receiving washer 80 incorporated in the heel below said boss.

3. A rubber lift for boots and shoes made concavo-convex; with integral boss upon 85 the top side of the lift to seat against the heel when the lift is applied thereto, the thickness of the lift from the top of said boss to the tread side of the lift being less than the thickness of the lift near its edge.

4. A rubber lift for boots and shoes made with a convex tread side and with its middle portion thinner than its marginal portion, and an integral boss upon the top side to seat against the heel when the lift is applied thereto.

5. A rubber lift for boots and shoes made 95 with a convex tread side and with its middle portion thinner than its marginal portion, and an integral boss upon the top side to seat against the heel when the lift is applied, the thickness of the lift through 100 said boss being less than the thickness near the edge of the lift.

6. A rubber lift for boots and shoes made with a convex tread side and with its middle portion of less thickness than its marginal portion; an integral ridge projecting 105 above the top side of the lift to seat against the shoe heel, the thickness of the lift through said ridge being less than the thickness through the lift near its edge, and 110 nail receiving means embedded in the lift immediately below said ridge.

7. A rubber lift for boots and shoes made with a convex tread side and a concaved top side, the middle portion of said lift being of less thickness than its marginal portion and said marginal portion being inwardly beveled; an integral ridge projecting above the top side of the lift inside of 115 said beveled marginal portion to seat against the shoe heel, the thickness of the lift through said ridge being less than the thickness through the lift near its edge, and nail receiving means embedded in the lift immediately below said ridge.

THOS. A. GAMBINO.
